UNITED STATES PATENT OFFICE.

WILLIAM H. MACKORELL AND DOUGLAS E. WINFREE, OF FORT SMITH, ARKANSAS.

LOCOMOTIVE-PILOT.

1,066,637.

Specification of Letters Patent.

Patented July 8, 1913.

Application filed October 5, 1912. Serial No. 724,108.

To all whom it may concern:

Be it known that we, WILLIAM H. MACKORELL and DOUGLAS E. WINFREE, citizens of the United States, residing at Fort Smith, in the county of Sebastian and State of Arkansas, have invented certain new and useful Improvements in Locomotive-Pilots; and we do hereby declare the following to be a full, clear, and exact description of the invention, such as will enable others skilled in the art to which it appertains to make and use the same.

Our invention relates to the construction of locomotive pilots, and has for its object the production of a simple, strong, durable, efficient and easily assembled device of this character which shall be readily adjustable to vary its vertical dimension and to vary its height above the rails, thus making a single type of pilot of uniform construction and dimensions suffice for all locomotive engines of standard gage, regardless of their size or class, and thus, also, rendering it unnecessary to disconnect and remove the pilot from the locomotive in the event that the breaking of a spring, spring-hanger, or the like, upon the locomotive should let the pilot down upon the track. Our invention, therefore, reduces the expense attendant upon constructing special pilots to fit locomotives of various different sizes and classes, and likewise reduces the cost of repairs and maintenance.

Generally stated, we accomplish the before-noted objects by forming the pilot with a vertically adjustable basal frame to which are pivotally secured the lower sections of telescoping ribs or slats, the upper sections of the laterally disposed slats or ribs being pivotally connected to the draw-beam of the locomotive or to breast plates thereon, the upper sections of the centrally arranged ribs being pivotally connected to a transversely extending support which is suspended from the draw-beam through the instrumentality of a plurality of the upper, laterally disposed rib-sections, and means being provided for vertically adjusting the basal plate and its pivotally attached lower rib-sections with respect to the draw-beam of the locomotive.

In the drawings chosen for the purpose of illustrating our invention, the scope whereof is pointed out in the claims, Figure 1 is a front elevation of a locomotive pilot embodying our invention, illustrating it as con-

nected to the draw-beam of a locomotive; Fig. 2 is a plan view of the construction shown in Fig. 1; Fig. 3 is a side elevation of the pilot, showing the pilot coupler and 60 showing also, in dotted lines, the pilot as adjusted to its uppermost position, whereby its vertical dimension is reduced; Fig. 4 is a sectional view, taken in the plane of the line 4—4, Fig. 1; Fig. 5 is a detail sectional view, taken in the plane of the line 5—5, Fig. 1; Fig. 6 is a view, partly in plan and partly in horizontal section, taken on the line 6—6, Fig. 5, further illustrating the detail of construction shown in Fig. 5; Fig. 7 70 is a detail sectional view, taken in the plane of the line 7—7, Fig. 3; Fig. 8 is a detail sectional view, taken in the plane of the line 8—8, Fig. 4; Fig. 9 is a detail cross-section of one of the telescoping ribs, the section being taken through the overlapping portions of the rib-sections, in the plane of the line 9—9, Fig. 1; Fig. 10 is a detail view corresponding to Fig. 9, but illustrating the form of cross-section of the central rib, the 80 view being taken in the plane of the line 10—10, Fig. 1; and Fig. 11 is a detail sectional view, taken in the plane of the line 11—11, Fig. 4.

Similar parts are indicated by corresponding reference letters throughout the several views.

We will now proceed to describe our invention more fully so that others, skilled in the art to which it appertains may apply 90 the same.

In the drawings, A indicates the draw-beam or pilot beam of a locomotive, and B the coupler secured thereto in the usual or any approved manner and projecting forwardly through a central opening B' in the upper part of the pilot.

The pilot itself may be broadly stated to consist of a telescoping frame in combination with telescoping ribs or slats the co-action of which parts enables the vertical dimension of the pilot to be increased or diminished so as to adapt the pilot to various sizes and classes of locomotives of standard gage, and also to allow the pilot to be raised 100 or lowered with relation to the track rails when, for any reason, such an adjustment becomes necessary or desirable.

The telescoping frame of the pilot, in the present instance, is shown as comprised of 110 breast-plates 1, 1 that are bolted to the draw-beam or pilot beam B of the locomo-

tive, vertically disposed telescoping hangers 2, 2 which adjustably support a triangular base-plate 3 at its rear, hangers 4, 4, in the form of turn-buckles, some of which serve to 5 adjustably support the base-plate 3 at its front, and a base-plate 3. The base-plate affords a frame for the attachment of the lower sections of telescoping ribs, while the breast-plates 1, 1 afford a support or place 10 of attachment for the upper sections of certain of the telescoping ribs or slats; and the telescoping ribs together with the frame constitute the pilot.

The upper sections of the hangers 2, 2, 15 which may be conveniently riveted to the breast-plates 1, as at 2^a, 2^a, are preferably channeled, as at 2^b, for the reception of the lower sections of said hangers, the latter being secured to the rear cross-bar 3^a of 20 base plate 3, as, for example, by rivets 2^c.

In order to maintain the proper relation and coaction of the upper and lower sections of the hangers 2, 2, as well as to permit their sliding one upon the other for purposes of adjustment, the coacting sections of 25 the hangers are connected by bolts 2^d (see Figs. 1 and 3), one of said sections of each hanger being provided with an elongated slot 2^e.

30 Instead of providing the intermediate vertical slides C, C (see Figs. 1, 2 and 4) with bolt and slot devices so that the slideable sections may be clamped together, as in the case of the hangers 2, the relatively movable sections of the slides C, C are, as shown, preferably unprovided with any clamping devices, since they serve as guides rather than as hangers.

Secured to the under face of the draw- 40 beam or pilot beam B rearwardly of and in line with the outer hangers 2, 2, are hanger braces 5, 5. The guiding and clamping bolts 2^d, before noted, preferably pass through these braces, as well as through the 45 hangers 2, 2.

4, 4 indicate turn-buckles, preferably four in number, the outer turn-buckles being disposed vertically and the intermediate turn-buckles extending diagonally down- 50 ward and forward from the breast-plates 1 to the forward angular member of the base plate 3, which they adjustably support in similar manner to the hangers 2, before noted. Two of the turn-buckles 4, 4, are 55 located near the lateral edges of the pilot, while the intermediate two are preferably located within those telescoping ribs 8 which constitute the lateral boundaries of the coupler opening B' of the pilot. These turn- 60 buckles are utilized to raise or lower the bottom member 3 of the telescoping frame to thus vary the vertical dimensions of the pilot and also its distance above the rails; and as the angle of inclination of the intermediate 65 turn-buckles must necessarily change in ac-

cordance with various adjustments of the pilot, the upper members of these turn-buckles are pivotally connected to brackets 4^e which are secured to the breast-plates 1. The lower members of these turn-buckles are in like manner pivoted on brackets 4^b 70 that are secured to the base plate 3 of the pilot frame.

6, 7 and 8 indicate a series of telescoping ribs or slats each comprised of two members the upper of which slides within the lower. These ribs incline downwardly and forwardly from the breast-plates 1, 1 to the base plate 3 and constitute the outer members of the pilot proper. The general cross-section of these ribs is in form of a channel, the free edges of the outer member being turned inward, as at 6^a (see Figs. 9 and 10), to confine the inner member. The central rib 6 is preferably curved or inclined forwardly from both sides at the front (see Fig. 10), while the forward faces of the lateral ribs or slats 7 and 8 are preferably of quadrantal form, as shown in Figs. 6 and 9 and are arranged to present a flat face or 80 web 7^a toward the central rib 6.

The length of the telescoping ribs 6, 7 and 8 appropriately varies according to the position each occupies in the pilot, as will be readily understood, the centrally disposed 95 ribs 6 and 7 being short to provide for the coupler opening B', and the outer ribs 8, which extend from the breast-plates 1 to the base-plate 3, being correspondingly longer and having pivotal connections with 100 both the breast-plates and the base-plate while the intermediate ribs 6 and 7 extend only from base-plate 3 to a cross bar or angle plate 9 to which their upper ends are pivoted. The pivotal connections at the upper and lower ends of all the ribs may be 105 conveniently made through bolts and brackets of the same character as those more particularly shown at 10 and 10^a in Figs. 5 and 6.

The angle plate 9 to which the upper 110 members of the telescoping ribs or slats 6 and 7 are pivoted is secured at its ends to the two inner main ribs 8, 8 that form the lateral boundaries of the coupler openings B' of the pilot. For this purpose the ends 115 of the angle plate are preferably closed or boxed, as by notching and folding the flanges of the angle plate in the form indicated in Fig. 5, and the lower members of the ribs are provided with elongated slots 8^a 120 (see Figs. 4 and 11) through which and through bolt holes in the upper members of said ribs 8 are passed bolts 9^a that extend through the ends of angle-plate 9, said bolts being provided with nuts for clamping the 125 ends of the angle-plate 9 to the adjacent ribs 8. In order to provide for the connection of the angle plate 9 to the ribs 8, and also to properly house the intermediate turn-buckles 4, as hereinbefore noted, these inner 130

or main ribs 8 on each side of the coupler opening B' are preferably made somewhat larger in cross-section than the remainder of the main ribs 8.

5 When the nuts on the bolts 9^a are loosened to permit the telescoping of the upper and lower sections of the ribs 8 to which the angle-plate 9 is attached, and after the nuts on the bolts 2^a of the hangers 2 are loosened 10 to permit the members of said hangers to slide on each other, the rotation of the turn-buckles 4 in the proper direction effects either a raising or lowering of the base-plate 3 of the frame as may be desired, thus 15 either increasing or decreasing the vertical dimensions of the pilot.

As hereinbefore noted, the ends of the telescoping slats or ribs 8 are pivotally connected with the breast-plates 1 and with the 20 base-plate 3, while the ends of telescoping slats or ribs 6 and 7 are similarly connected with the angle-plate 9 and with the base-plate 3. These pivotal connections may be advantageously made through brackets and 25 pivot bolts of the character more particularly illustrated at 10 and 10^a in Figs. 5 and 6. The brackets 10, as shown, are preferably of U-shape in cross-section and are curved or bent to properly fit inside of the 30 ribs and permit the pivotal movement of the latter on bolts 10^a which connect the ribs and brackets.

In order to make provision for changes in the angle of inclination of the ribs 6, 7 and 35 8 incident to the vertical movement of base plate 3, the ends of the telescoping ribs adjacent to their pivotal connections are rounded or beveled, as at 10^b and 10^c, so that when the pilot is adjusted to its full 40 height, as indicated in full lines in Figs. 3 and 4, the upper ends of the upper sections of the ribs engage the breast-plate 1 and the angle-plate 9, respectively, and the lower ends of the lower rib-sections engage the 45 base-plate 3.

We claim:

1. In a locomotive pilot, the combination of frame members adjustable with relation to each other to change the vertical dimension of the pilot, and ribs comprising members which are adjustable on each other to vary the length of said ribs.

2. In a locomotive pilot, the combination of a frame having members adjustable with 55 respect to each other to change the vertical dimension of the pilot, and ribs comprising members longitudinally adjustable upon each other to change the length of said ribs, the ribs at their opposite ends being pivotally connected with said frame.

3. In a locomotive pilot, the combination with a frame having a base plate, a breast-plate, and interposed vertically disposed hangers which are adjustable in length, of ribs comprising members that are adjustable 65 longitudinally with respect to each other.

4. In a locomotive pilot, the combination with a frame having a base-plate and vertically disposed hangers comprised of members which are longitudinally adjustable 70 with respect to each other to change the length of said hangers, of ribs comprised of members which are longitudinally adjustable with respect to each other to change the length of said ribs, and means 75 for adjusting said frame members and ribs.

5. In a locomotive pilot, the combination with a frame having breast-plates and a base-plate adjustable toward and from the breast-plates, of a series of ribs comprised 80 of members which are longitudinally adjustable with respect to each other, and turn-buckles which adjustably connect the breast-plates and base-plate.

6. In a locomotive pilot, the combination 85 with a frame having members which are vertically adjustable toward and from each other to change the vertical dimension of the pilot, of a series of ribs of different lengths, said ribs comprising members 90 which are longitudinally adjustable with respect to each other, the centrally disposed ribs being shorter than the laterally disposed ribs, and a transversely extending member to which the upper members of the 95 centrally disposed ribs are connected, said transversely extending member being connected to the adjacent laterally disposed ribs.

7. In a locomotive pilot, the combination 100 with a frame comprised of members which are vertically adjustable toward and from each other to change the vertical dimension of the pilot, of ribs comprised of members which are longitudinally adjustable with 105 respect to each other to change the length of said ribs, said ribs having beveled ends and being pivotally connected to the frame members adjacent to said beveled ends, and means for adjusting the frame members 110 vertically toward and from each other.

In testimony whereof we affix our signatures, in the presence of two subscribing witnesses.
